UNITED STATES PATENT OFFICE.

OCTAVER L. DESCHAMPS, OF PARIS, FRANCE.

MACHINE FOR CUTTING THE GIMP OR EMBROIDERY THREADS IN LACES, TULLES, &c.

SPECIFICATION forming part of Letters Patent No. 244,986, dated August 2, 1881.

Application filed April 8, 1881. (No model.) Patented in France February 15, 1881.

To all whom it may concern:

Be it known that I, OCTAVER LÉON DESCHAMPS, of Paris, in the Republic of France, have invented a new or Improved Machine for 5 Cutting the Gimp or Embroidery Threads in Tulles, Laces, Valenciennes Embroidery, and Tarlatans, (for which I have obtained Letters Patent of France for fifteen years, dated February 15, 1881;) and I do hereby declare that 10 the following is a full, clear, and exact description thereof, reference being made to the accompanying drawings.

In the manufacture of tulles, laces, valenciennes embroideries, tarlatans, and other similar fabrics by machinery, the mechanical production of the designs necessitates the use of embroidery threads and gimps, which assist in the formation of flowers and other designs. The said embroidery threads and gimps have 15 to be cut afterward, between each of the aforesaid flowers or other design, because they are useless and incumber the back of the tissue.

Heretofore the cutting of the embroidery threads or gimps has been done by hand, and 20 this is a difficult and costly process. By means of my new apparatus, hereinafter described and illustrated, this work is done mechanically.

My new machine is able to cut the gimp or embroidery threads in all kinds of tulles, laces, &c., whatever may be the shape of the designs or the nature of the tissue. It cuts better and 25 more quickly than can be done by hand, and never pierces the tissue.

Figure 1 is a vertical central section of the 30 apparatus. Fig. 2 is a sectional plan view; and Fig. 3 the plan of a modification.

In a wooden handle, *a*, is fixed a metallic tube, *b*, which is cast or connected to three arms, *c' c' c'*, that terminate in a ring, *c*. Through 35 the tube *b* is passed a rod, *d*, which constitutes the shaft of the mechanism. At the upper end of this shaft is fixed a pulley, *e*, whose hub *e'* rests on the tube *b*. Around the hub *e'* is swiveled a bar or disk, *f'*, which carries two 40 friction-rollers, *ff'*. These rollers are intended to guide the rope which gives motion to the pulley *e*, and to hold it close to the pulley *e* sufficiently for driving it.

To the lower end of the shaft *d* is joined, by 45 a nut, *d'*, a socket, *g'*, which has three radially-

projecting arms, *g g g*, that carry the cutting-disks *h*. These disks *h* are fixed on vertical pins *i* that hang in the arms *g*, and that carry pinions *p*, all gearing into an annular rack, *m*. This rack *m* is attached to the arms *c' c' c'* of 55 the ring *c*. Within the ring *c* is secured an inner ring, *n*, having an inwardly-projecting horizontal cutting-flange *l*. The cutters *h* bear on this flange, and are held down on it by springs *r* that press upon the pins *i*.

To the outer side of the ring *c* is fastened an extension-arm, *s*, whose edges, near its upper end, *s'*, are sharpened to cut. On top of the arm *s* are two blades, *t t*, which cross each other, the upper blade, *t'*, having its free end 60 slightly curved upward to keep it from entering beneath the gimp or embroidery threads.

The lower faces of the arm *s*, and of the cutting-flange *l*, must be strictly in the same plane.

The machine operates as follows: By means 70 of a convenient transmission a rope gives rotary motion to the pulley *e*, and consequently to the arms *g* which carry the cutting-disks *h*. The pinions *p*, meshing into rack *m*, are thereby also rapidly revolved around their axes. 75 The apparatus being firmly held in hand and caused to act, is moved in varying directions over the tulle or fabric whose gimp-threads are to be cut. The operator watches attentively the end of the arm *s*, and directs it underneath 80 the embroidery or gimp threads. The arm *s* cuts these threads, either near their ends or, by the blade *t t'*, in the middle. The ring *c*, being kept firmly on the fabric as it is fed along, raises the cut-threads and causes them to 85 stand up, so that they are readily clipped off by the cutters *h*, acting on ring-blade *l*. These threads are thereby clipped close to the fabric.

In order not to miss clipping any threads which the blade *s* has cut open I may provide 90 the lower side of the ring *c* with a ring or lining of felt, *x*, or any other frictional material, such as india-rubber. Such a felt ring can be held in place by an outer ring, *x'*, as shown.

In Fig. 3 I show that the arm *s* can be projected into the ring *l* instead of projecting outward, as in Figs. 1 and 2. For the steel disks *h*, whose number is variable, I may substitute 95 equivalent rotary knives.

The ring *c* may contain arms or inward pro- 100

jections, which assist in raising the gimp or embroidery threads and presenting them to the knives.

I claim—

- 5 1. The gimp cutting and clipping instrument consisting, essentially, of the rotating cutters *h h*, carried on a revolving shaft, *d*, the fixed annular blade *l*, handle *a*, and of the cutting-arm *s*, all combined to operate substantially 10 as herein shown and described.
2. The combination of the blades *t t'*, with cutting-arm *s*, ring *c*, ring-blade *l*, rotating knives *h*, and handle *a*, substantially as herein shown and described.
- 15 3. A gimp cutting and clipping apparatus constructed with a cutting-blade, *s*, and with

rotary clipping-cutters *h*, arranged to revolve within an embracing ring or cup, *c*, substantially as specified.

4. The combination of shaft *d* and its pulley *e*, with the arms *g g*, pins *i*, pinions *p*, cutters *h*, rack *m*, and annular blade *l*, substantially as herein shown and described. 20

5. The combination of the cutters *h* and their pins *i*, with the springs *r*, and annular 25 blade *l*, and with means, substantially such as described, for revolving said cutters, all as set forth.

O. L. DESCHAMPS.
